ELECTRICAL OUTLET CONSTRUCTION

Filed Dec. 8, 1945

UNITED STATES PATENT OFFICE

2,437,579

ELECTRICAL OUTLET CONSTRUCTION

Robert E. Wilson, Minneapolis, Minn.

Application December 8, 1945, Serial No. 633,749

6 Claims. (Cl. 173—334.1)

1

My invention relates to a novel continuous electrical outlet construction and has for its object the provision of such a construction which is economical to manufacture, easy to assemble, and is quick and fool-proof to operate.

A further object of my invention is the provision of a continuous outlet strip which has great utility and may be as readily adapted for Christmas tree lights and the like, as to the wiring of a room.

The above and still further objects of my invention will become apparent from the following specification, attached drawings, and appended claims.

Referring to the drawings wherein like characters indicate like parts throughout the several views:

Fig. 1 is a perspective view;

Fig. 2 is a view partly in side elevation and partly in section taken on the line 2—2 of Fig. 1;

Fig. 3 is a side elevational view;

Fig. 4 is a transverse sectional view taken on the line 4—4 of Fig. 3;

Fig. 5 is a transverse sectional view similar to Fig. 4, but showing the terminal head turned to a power take-off position;

Fig. 6 is a fragmentary detailed view;

Fig. 7 is a side elevational view showing a modified form of contact finger;

Fig. 8 is a bottom elevational view of Fig. 7; and

Fig. 9 is a sectional view of a modified form of outlet strip, some parts being shown by dotted lines.

Referring with greater particularity to the drawings, the numeral 1 indicates a flexible resilient insulating strip, preferably made of natural or synthetic rubber. Strip 1, as shown, is preferably substantially rectangular in form so as to have parallel upper and lower faces 2 and 3, respectively, as well as substantially parallel sides. Within strip 1 are a pair of longitudinally extending laterally spaced parallel passages 4. Self-closing slits 5 extend inwardly from the opposite side edges of strip 1, each to an adjacent passage 4. Longitudinally extending electrical conductors, in the form of flexible wires or cables 6, are snugly fit into passages 4.

Adapted to cooperate with the above described novel conduit is a contact or terminal head 7 which may be molded from rubber, Bakelite, or other suitable insulating materials. Head 7, as shown, is preferably of a circular form around its center as indicated at 8, has a tapering top 9, and a pair of depending legs 10 which are

2

spaced apart at 11 so as to provide a passage into which strip 1 is adapted to snugly fit. As will be observed, passage 11 flares outwardly in opposite directions from its intermediate portion to permit limited rotation of the terminal head 7 on strip 1. It will also be observed that because of the outwardly flaring shape of the passages 11 that the legs 10, which straddle the strip 1, are segmental in cross-sectional shape, their closest points indicated by the numeral 10' being spaced apart only a slightly greater distance than the width of the strip 1.

The upper surface of passage 11 is preferably flat, as indicated at 12, so as to lie flush with the flat upper surface 2 of strip 1 and thus prevent rocking of the head 7 as it is rotated thereon. A conventional electrical conduit 13 having therein a pair of spaced electrical conducting wires or the like 14 enters the opening 15 in the tapering top 9 of head 7. Within a cavity 16 in the head 7 the conductor wires 14 terminate in contact with a pair of laterally spaced vertically extending terminal arms 17 which are rigidly secured to head 7 in any desired manner. Terminal arms 17 extend downwardly beyond the flat upper surface 12 and into the passage 11 a distance only equal to approximately half the thickness of strip 1, where the bottom ends 18, shown as preferably being bifurcated so as to provide a pair of laterally spaced contact fingers 19 and 20, are bent at approximately right angles. As will be observed by reference particularly to Figs. 4 and 5, terminal arms 17 are so situated with respect to the depending legs 10, which straddle strip 1, that the contact fingers 19 and 20 extend laterally inwardly from opposite sides of opposite flared ends of passage 11 and are adapted to enter opposite slits 5 of strip 1 under rotation of the head 7 in one direction, and make contact with the electrical conductors 6 in passages 4. As shown in Figs. 2, 3 and 6, the contact fingers 19 and 20 are slightly staggered so that as they enter the slits 5 and make contact with the electrical conductors 6, one will frictionally over-ride the same, and the other will be inclined to frictionally under-ride the conductor 6.

In Figs. 7 and 8, I have shown a structure similar in all respects to those above described but having only a single contact finger 21 having a knife-like tapering frontal edge 22.

As shown particularly in Fig. 1, the spaced legs 10 are provided at their bases with feet 23 which project laterally at approximately right angles in the same direction as contact fingers 19 and 20. Furthermore, feet 23 are so spaced vertically with

respect to upper surface 12 of passage 11 and contact fingers 19 and 20, that when head 7 is rotated in a direction to force contact fingers 19 and 20 into slits 5 and into contact with conductors 6, the said feet 23 will frictionally engage the bottom side 3 of strip 1 and tend to hold the head 7 in a locked position on strip 1. As shown particularly in Figs. 2 and 3, the toes 24 of feet 23 are preferably provided with raised portions 24', which when made to pass over the conduit containing portions of strip 1, tend to lodge in the center of the strip and provide an even more satisfactory means of locking the plug against accidental removal.

The structure shown in Fig. 9 is identical in all respects to that shown in Figs. 1 to 5 except that the under surface 3' is provided with a depending continuous, centrally located rib 25, from the bottom of which a base flange 26 projects laterally, thereby forming opposed channels 27. In this construction, which is particularly adapted to be nailed onto a floor or the like by means of small nails 28, the toes 24 of feet 23 are adapted to come to rest within the opposite channels 27 when the contact fingers 19 and 20 are in engagement with the conductors 6'.

While I have described above the preferred embodiment of my invention, it should be obvious that the invention is subject to modifications without departing from the scope of the appended claims.

What I claim is:

1. An electrical outlet construction comprising laterally spaced electrical conductors disposed within a substantially rectangular insulating member, the opposite sides of said insulating member being provided with self-closing slits which project inwardly each to an adjacent one of said conductors, a terminal head having a passage therethrough to receive the insulating member, said passage flaring outwardly in opposite directions from its intermediate portion to permit limited rotation of the terminal head on the insulating member, contact fingers carried by the head and extending inwardly from opposite sides of opposite flared ends of said passage and adapted to enter opposite slits in the insulating member under rotation of the terminal head in one direction, and feet carried by the head and extending inwardly from the opposite sides of opposite flared ends of said passage and adapted to frictionally grip the lower face of said insulating member when the contact fingers are forced to enter the opposite slits of the insulating member under rotation of the terminal head.

2. A continuous electrical outlet construction comprising a strip of flexible insulating material, longitudinally extending laterally spaced parallel passages within said strip, slits extending inwardly from opposite edges of said strip each to an opposite of said passages, electrical conductors in said passages, a terminal head having a passage therethrough to receive the insulating strip, said passage flaring outwardly in opposite directions from its intermediate portion to permit limited rotation of the terminal head on the insulating strip, contact fingers carried by the head and extending laterally inwardly from opposite sides of opposite flared ends of said passage and adapted to enter opposite slits in the insulating strip under rotation of the terminal head in one direction, and feet carried by said head and extending inwardly from the opposite sides of opposite flared ends of said passage and adapted to frictionally grip the under surface of the insulat-

ing strip when the contact fingers are forced to enter the opposite slits of the insulating strip under rotation of the terminal head.

3. A continuous electrical outlet construction comprising a strip of readily flexible resilient insulating material of generally rectangular cross-sectional shape, longitudinally extending laterally spaced parallel passages within said strip, self-closing slits extending inwardly from the side edges of said strip and communicating with an opposite of said passages, flexible electrical conductors in said passages, a terminal head overlying said strip, a pair of opposed depending legs carried by said head and straddling said insulating strip, said legs defining a passage which flares outwardly in opposite directions from its intermediate portion to permit limited rotation of the terminal head on said insulating strip, and contact fingers carried by the legs and extending laterally inwardly from opposite sides of opposite flared ends of said passage and adapted to enter opposite slits in the insulating strip under rotation of the terminal head in one direction.

4. The structure defined in claim 3 in further combination with feet carried by said legs and extending inwardly from the opposite sides of opposite flared ends of said passage and adapted to frictionally grip the under surface of the insulating strip when the contact fingers are forced to enter the opposite slits of the insulating strip under rotation of the terminal head.

5. A continuous outlet construction comprising a flexible resilient insulating strip having substantially parallel upper and lower surfaces, longitudinally extending laterally spaced passages within said strip, slits extending inwardly from opposite edges of said strip each to an opposite of said passages, electrical conductors in said passages, a longitudinally extending central rib depending from the lower surface of said strip and terminating in an enlarged base flange substantially parallel with the upper and lower surface of said strip, said base flange, rib and insulating strip defining a pair of opposed channels, a terminal head overlying the upper surface of said insulating strip, a pair of legs depending from said head and straddling said insulating strip, said legs defining a passage which flares outwardly in opposite directions from its intermediate portion to permit limited rotation of the terminal head on said insulating strip, contact fingers carried by the legs and extending laterally inwardly from opposite sides of opposite flared ends of said passage and adapted to enter opposite slits in the insulating strip under rotation of the terminal head in one direction, and feet carried by said legs and also extending laterally inwardly from the opposite sides of opposite flared ends of said passage and adapted to make frictional engagement with the opposed channels when the contact fingers are forced to enter opposite slits of the insulating strip under rotation of the terminal head.

6. A terminal head adapted to cooperate with an electrical outlet, said outlet comprising laterally-spaced electrical conductors disposed within a rectangular insulating member, the opposite sides of said insulating member being provided with self-closing slits which project inwardly each to an adjacent one of said conductors, said terminal head having therethrough a passage adapted to receive the insulating member, said passage flaring outwardly in opposite directions from its intermediate portion to permit limited rotation of the terminal head on said insulating member,

contact fingers carried by the head and extending inwardly from opposite sides of opposite flared ends of said passage and adapted to enter opposite slits in the insulating member under rotation of the terminal head in one direction, and feet carried by the head and extending inwardly from opposite sides of opposite flared ends of the passage and adapted to frictionally grip the lower face of said insulating member when the contact fingers are forced to enter the opposite slits of the insulating member under rotation of the terminal head.
